UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

SPECIFICATION forming part of Design No. 12,132, dated January 18, 1881.

Application filed December 6, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

10 The design is composed of an Egyptian landscape, comprising pyramids, camels, and palm-trees, involved angular stripes A, rectangular figures B, circular figures C, ornamented by basket-work and partially covering the figures B, and floral and foliage designs, as shown, interspersed between the features above named and partly covering some of said features.

I claim—

15 The design for a carpet having an Egyptian landscape, the figures A, B, and C, and the floral and foliage designs, substantially as shown and described.

In testimony whereof I have signed my name to this specification, in the presence of two subscribing witnesses, this 3d day of December, 1880.

THOMAS J. STEARNS.

Witnesses:

DAVID McNAIR,
WILLIAM SCHMIDT.
